(Cl. D56—2)

The figure is a perspective view of an organ console, showing our new design.

The side of the organ console not shown is the same as the side shown. The back of the organ console is plain.

The dominant features of our design reside in the portions shown in full lines and more specifically in a flat top surface having a shallow rectangular recessed area at the front edge thereof, in combination with downwardly and forwardly curving side arms which are slightly inset relative to the organ top and sides together with the particularly shaped music desk and legs, all as shown.

We claim:

The ornamental design for an organ console, substantially as shown and described.
